BALL DETENT FASTENER WITH BALL AND SOCKET PLUNGER ASSEMBLY

Duane W. Price and David Z. Chapman, Los Angeles, Calif., assignors, by mesne assignments, to Aerpat A.G., Glarus, Switzerland, a corporation of Switzerland

Filed Jan. 10, 1958, Ser. No. 703,095

3 Claims. (Cl. 85—5)

The present invention relates in general to fasteners, and, more particularly, to a quickly releasable fastening device of the type utilized to hold together temporarily two or more plates, or other structural elements, by inserting it into registering holes therein, a general object being to provide an improved fastening device of this general character.

Still more particularly, the present invention contemplates a fastening device which includes: a barrel having one or more radial holes therethrough adjacent one end thereof, and having adjacent the other end thereof an external shoulder which faces said one end thereof and which serves as a stop for limiting insertion of the barrel into registering holes in structural elements to be secured together temporarily; a detent in each of the radial holes in the barrel and movable inwardly and outwardly therein between inner, retracted and outer, extended positions, each such detent projecting laterally from the barrel when in its extended position to prevent withdrawal of the barrel from the registering holes in the structural elements through which the barrel extends; a longitudinal plunger or pin movable axially in the barrel between operative and inoperative positions and having means thereon adjacent one end thereof for moving the detent or detents outwardly into its or their extended position or positions when the longitudinal pin is in its operative position; spring means engaging the barrel and the longitudinal pin and biasing the latter toward its operative position, such spring means including a compression coil spring encircling the longitudinal pin and seated on axially spaced internal and external shoulders on the barrel and the longitudinal pin, respectively, which face each other; and means for limiting axial movement of the longitudinal pin beyond its operative position by the spring means.

With such a fastening device, the detent or detents are permitted to move inwardly to retract same by moving the longitudinal pin axially into its inoperative position in opposition to the action of the spring means, whereupon the fastening device may be inserted into registering holes in the structural elements to be held together temporarily, the external shoulder on the barrel limiting insertion of the fastening device. When the longitudinal pin is released, the spring means returns it to its operative position to extend the detent or detents, which then prevent withdrawal of the fastening device from the registering holes in the elements to be secured together.

The primary object of the invention is to provide a fastening device of the foregoing type wherein the longitudinal pin is movable axially from its operative position to its inoperative position in opposition to the action of the spring means by means of a button or plunger which is a separate element from the longitudinal pin and which is disposed in and movable axially of the barrel adjacent the opposite end of the barrel from the detent or detents, such plunger having an end which projects from such opposite end of the barrel and having its other end seated against one end of the longitudinal pin.

Another object of the invention is to provide such a plunger having a longitudinally elongated aperture which extends diametrically therethrough and which receives a transverse pin extending through the barrel to limit move-

2

ment of the longitudinal pin beyond its operative position by the spring means.

Another object of the invention is to provide the end of the longitudinal pin which is seated against the plunger with a convex surface, the corresponding end of the plunger being concave and receiving the convex end of the longitudinal pin.

With the foregoing construction, i.e., with a construction wherein the longitudinal pin and the actuating plunger therefor are separate elements, the plunger and the longitudinal pin may be displaced axially of the barrel between the operative and inoperative positions of the longitudinal pin without binding irrespective of manufacturing inaccuracies in the barrel, the longitudinal pin and the plunger, there being no necessity for maintaining precise coaxiality among these components so that greater manufacturing tolerances are permissible. Also, providing the longitudinal pin with a convex end which is disposed in a concave end of the plunger results in what amounts to a ball-and-socket connection between the longitudinal pin and the plunger which compensates for any lack of precise coaxiality between the plunger and the longitudinal pin. Further, making the longitudinal pin and its actuating plunger as separate elements facilitates assembly and disassembly of the fastening device.

Another object of the invention is to provide a fastening device wherein the transverse pin which extends through the diametral, longitudinally elongated aperture in the plunger projects radially from the barrel on at least one side thereof to provide a convenient finger grip for opposing the reaction of pressure applied to the projecting end of the plunger in moving the longitudinal pin from its operative position to its inoperative position in opposition to the action of the spring means. A related object is to provide a transverse pin with a portion of reduced diameter disposed in the aperture in the plunger and having a length at least equal to the diametral length of the aperture in the plunger, whereby the shoulders provided at the ends of the reduced-diameter portion of the transverse pin engage opposite sides of the plunger to tend to prevent removal of such transverse pin.

Another object is to provide a fastening device having as a finger grip for opposing the reaction of an actuating force supplied to the projecting end of the plunger, an annular flange adjacent the plunger end of the barrel.

Another object is to provide a finger grip for the foregoing purpose comprising a bail the ends of which are pivotally connected to projecting ends of the transverse pin which extends through the barrel and the aperture in the plunger.

The foregoing objects, advantages, features and results of the present invention, together with various other objects, advantages, features and results thereof which will be evident to those skilled in the art in the light of this disclosure, may be attained with the exemplary embodiments of the invention illustrated in the accompanying drawing and described in detail hereinafter. Referring to the drawings:

FIG. 1 is a longitudinal sectional view of a fastening device of the invention being inserted into registering holes in elements to be held together;

FIG. 2 is a longitudinal sectional view of the fastening device after such insertion;

FIGS. 3 and 4 are transverse sectional views respectively taken along the arrowed lines 3—3 and 4—4 of FIGS. 1 and 2; and

FIGS. 5 and 6 are perspective views of other embodiments of the invention.

Referring to FIGS. 1 to 4 of the drawing, illustrated therein is a fastening device 10 of the invention which is insertable through registering holes 12, 14 and 16 in plates 18, 20 and 22, or other structural elements, to

hold same together temporarily. Obviously, the device 10 may be used with numbers of structural elements greater or less than the specific number shown.

The fastening device 10 includes a tubular barrel 24 having a convergent or tapered end 26 to facilitate insertion of the barrel into the holes 12, 14 and 16, the barrel 24 having at its other end a cylindrical enlargement or head 28 which provides an external annular shoulder 30 engageable with the assembly of plates 18, 20 and 22 to limit insertion of the barrel.

The barrel 24 is provided adjacent the tapered end 26 thereof with two aligned, radial holes 32 for ball detents 34 which are movable inwardly and outwardly between inner, retracted positions, shown in FIG. 1, and outer, extended positions, shown in FIG. 2. The detents 34 prevent withdrawal of the barrel 24 from the holes 12, 14 and 16 when in their extended positions. Loss of the detents 34 from the holes 32 is prevented by peening or staking the barrel adjacent the outer ends of the holes, as indicated at 36.

Reciprocable in an axial bore 38 in the barrel 24 and extending into a substantially coaxial counterbore 40 in the head 28 of the barrel is a longitudinal pin 42 having a longitudinally-arcuate reduced-diameter portion 44 adapted to receive the ball detents 34 therein to permit them to move inwardly into their retracted positions. The reduced diameter portion 44 of the longitudinal pin 42 is in register with the holes 32 to permit the detents 34 to move inwardly into their retracted positions when the longitudinal pin is in an inoperative position, shown in FIG. 1 of the drawing. When the longitudinal pin 42 is in an operative position, shown in FIG. 2 of the drawing, an end portion 46 thereof of a diameter exceeding that of the portion 44 registers with the holes 32 to move the detents 34 outwardly into their extended positions, the end portion 46 of the longitudinal pin thus serving as a means for extending the detents to prevent withdrawal of the barrel 24 from the assembly of members 18, 20 and 22.

The longitudinal pin 42 is provided within the head 28 of the barrel 24 with a head 48 which provides an external annular shoulder 50 facing and spaced axially from an internal shoulder 52 on the barrel 24 at the junction of the bore 38 and the counterbore 40. Encircling the longitudinal pin 42 and seated on the shoulders 50 and 52 is a compression coil spring 54 which serves as a means for biasing the longitudinal pin 42 from its inoperative position toward its operative position.

The head 48 on the longitudinal pin 42 is shown as providing the latter with a convex end 56 which is seated against a concave end 58 of an actuating button or plunger 60, i.e., which is disposed in a concave recess 62 in the end 58 of the plunger 60. The plunger has an outer end 64 which projects axially from the head 28 of the barrel 24 and which is engageable by the thumb 66 of an operator to move the plunger axially toward the tapered end 26 of the barrel 24, thereby simultaneously moving the longitudinal pin 42 axially from its operative position to its inoperative position to permit retraction of the detents 34 for the purpose of inserting the barrel through the holes 12, 14 and 16.

The plunger 60 is shown as provided intermediate its ends with a diametral, longitudinally elongated aperture 68 which receives a transverse pin 70 extending through the head 28 of the barrel 24 and disposed in aligned radial holes 72 therein. The transverse pin 70 is provided with a reduced-diameter portion 74 disposed in the aperture 68 and having a length equal to the diametral dimension of the aperture, the reduced-diameter portion 74 having at its ends shoulders 76 which engage the plunger 60 in the vicinities of the ends of the aperture 68 to prevent inadvertent removal of the transverse pin.

The transverse pin 70 serves the function of limiting movement of the longitudinal pin 42 beyond its operative position, the longitudinal pin being in its operative position, as shown in FIG. 2, when one end of the longitudi-

nally elongated aperture 68 is in engagement with the transverse pin. Similarly, the transverse pin 70 prevents movement of the longitudinal pin 42 beyond its inoperative position, as shown in FIG. 1, the other end of the elongated aperture 68 engaging the transverse pin under such conditions.

The transverse pin 70 is provided with projecting portions 78 on opposite sides thereof which serve as handles or grips for two fingers 80 of the operator to oppose the reactive force resulting from application of thumb pressure to the outer end of the actuating plunger 60 in moving the longitudinal pin 42 to its inoperative position to permit retraction of the ball detents 34.

It is thought that the operation of the fastening device 10 will be obvious from the drawing and the foregoing description. Briefly, the operator grasps the fastening device 10 as shown in FIG. 1 of the drawing with his thumb 66 and fingers 80 and moves the plunger 60 inwardly sufficiently to move the longitudinal pin 42 into its inoperative position, thereby permitting retraction of the ball detents 34. The operator then inserts the tapered end 26 of the barrel 24 into the holes 12, 14 and 16 until the shoulder 30 engages the plate 18. Thereupon, the operator releases the fastening device so that the spring 54 returns the longitudinal pin 42 to its operative position to extend the detents 34. The fastening device 10 is now locked in place until such time as it is released for removal.

It will be noted that, by making the longitudinal pin 42 and the actuating plunger 60 therefor as two separate parts, these parts cannot bind in the barrel 24 despite manufacturing inaccuracies, such as coaxiality inaccuracies. The convex end 56 of the longitudinal pin 42 and the concave end 58 of the plunger 60 provide, in effect, a ball-and-socket joint which compensates for any deviation from precise coaxiality.

In FIG. 5 of the drawing is illustrated a fastening device 90 which is identical to the device 10 except that, instead of being provided with the transverse pin 70, it is provided with a shorter transverse pin 92 the ends of which extend through the ends of a bail 94 which serves as a finger grip. The ends of the pin 92 are preferably riveted over the ends 94 of the bail loosely to permit the bail to pivot relative to the barrel of the device 90.

Referring to FIG. 6, illustrated therein is a fastening device 100 which is identical to the fastening device 10 except that again a shorter pin 102 is substituted for the transverse pin 70, the pin 102 being a longitudinally split, tubular pin which is locked in place by its tendency to expand circumferentially within the holes in the barrel. The pin 102 retains an outer bushing 104 having thereon an annular flange 106 at the end of the barrel which houses the plunger 60, this flange serving as a finger grip.

Although exemplary embodiments of the invention have been disclosed herein for purposes of illustration, it will be understood that various minor changes, modifications and substitutions may be incorporated in such embodiments without departing from the spirit of the invention as defined by the claims which follow.

We claim:

1. A fastening device comprising a barrel having first and second bores each of a different diameter which form an interior shoulder near the middle portion of said barrel, the smaller diameter bore portion of said barrel having at least one radial hole near the outer end thereof, an elongated pin mounted for free axial movement in said smaller bore, one end of said pin extending into said larger bore and terminating in an enlarged head having a rounded top surface in the form of a convex spherical segment, said pin having a circumferential recess near the other end to provide a seat for a ball detent located in said radial hole, means on said pin for outwardly urging said ball detent partially through said radial hole when brought into register therewith to fasten said barrel

in place, a loosely fitted actuating plunger axially movable within the larger diameter bore, means to limit the plunger movement within said larger diameter bore, a recess in said plunger having a surface in the form of a convex spherical segment complementary in shape to and facing said rounded head of said pin to provide a ball and socket engagement between the complementary surfaces, spring means urging said rounded head of said pin against the complementary recess of said plunger whereby when said plunger is moved against the urging of said spring means, the ball and socket engagement of the complementary surfaces and said spring means causes an axial self centering of said loosely fitted plunger and pin to prevent the binding thereof in said bores.

2. In a fastening device of the type comprising a barrel having first and second bores each of a different diameter which form an interior shoulder near the middle portion of said barrel, the smaller diameter bore portion of said barrel having at least one radial hole near the outer end thereof, an elongated pin mounted for free axial movement in said smaller bore, one end of said pin extending into said larger bore and terminating in an enlarged head having a rounded top surface in the form of a convex spherical segment, said pin having a circumferential recess near the other end to provide a seat for a ball detent located in said radial hole, means on said pin for outwardly urging said ball detent partially through said radial hole when brought into register therewith to fasten said barrel in place, said improvement comprising a loosely fitted actuating plunger axially movable within the larger

diameter bore, means to limit the plunger movement within said larger diameter bore, a recess in said plunger having a surface in the form of a concave spherical segment complementary in shape to and facing said rounded head of said pin to provide a ball and socket engagement between the complementary surfaces, spring means urging said rounded head of said pin against the complementary recess of said plunger whereby when said plunger is moved against the urging of said spring means, the ball and socket engagement of the complementary surfaces and said spring means causes an axial self centering of said loosely fitted plunger and pin to prevent the binding thereof in said bores.

3. Apparatus according to claim 1, wherein said means to limit the movement of said plunger comprises in combination a longitudinally elongated aperture in said plunger and a transverse pin carried by the larger diameter bore portion of said barrel and extending through said plunger aperture.
